UNITED STATES PATENT OFFICE

JAMES FRANK ROGERS, OF NORTH ATTLEBORO, MASSACHUSETTS, ASSIGNOR, BY MESNE ASSIGNMENTS, TO ART METAL WORKS, INC., OF NEWARK, NEW JERSEY, A CORPORATION OF NEW JERSEY

CIGAR LIGHTER

Application filed October 31, 1930. Serial No. 492,459.

This invention relates to a novel cigar lighter construction.

One of the objects of this invention is the provision of a novel cigar lighter structure having resilient means coordinating the snuffer arm and flint cutting mechanism so that actuation of the snuffer arm to remove it from the "snuffing position" concurrently actuates the flint cutting mechanism to ignite an inflammable wick.

Various other objects and advantages of the invention than those hereinabove mentioned will appear more fully hereinafter. It is to be understood that the specific form of the invention hereinafter shown is merely illustrative and hence the detailed description thereof is not to be taken as limiting.

The invention resides substantially in the combination, construction, location, and relative arrangement of parts, all as will be more fully pointed out hereinafter.

In the accompanying drawing:

Figure 1 is a view in side elevation of the upper part of my novel cigar lighter with the snuffer arm in partially raised position;

Fig. 2 is a top plan view thereof;

Fig. 3 is a sectional view taken along the line 3-3 in Fig. 2;

Fig. 4 is a sectional view taken along the line 4-4 in Fig. 2;

Fig. 5 is a sectional view taken along the line 5-5 in Fig. 1;

Fig. 6 is an end view of the snuffer arm structure used in my novel cigar lighter;

Fig. 7 is a view in side elevation of a novel cap for sealing off the cigar lighter container body;

Fig. 8 is an end view of the threaded flint tube plug used with the cigar lighter;

Fig. 9 is a side view of the threaded flint tube plug shown in Fig. 8.

Similar reference characters refer to similar parts throughout the several views of the drawing.

Heretofore in the art of cigar lighters substantial difficulty has been encountered in the provision of a single operation cigar lighter wherein thumb pressure upon a single element functioned to raise a snuffer arm and simultaneously rotate a flint cutting wheel to

provide a shower of sparks for igniting an inflammable wick while removal of such thumb pressure permitted the return of the lighter parts to original position. Structures have been devised wherein thumb pressure is applied to raise a sectional snuffer arm from a wick and due to a ratchet-catch cam action spin a cutting wheel. These structures, however, have been found objectionable inasmuch as they are subject to catching, jamming and general lack of ruggedness.

It is the purpose of this invention to provide, therefore, a simplified novel cigar structure free from sluggishness, lack of ruggedness, difficulty of manipulation of parts, general instability of parts, as well as from catching effect between the various elements thereof. To attain this there is provided in my structure a mechanism adapted to give single operation action upon the pressure of the user's thumb being applied along a line substantially perpendicular to the plane of the top plate of the lighter, and in which also there are means for readily adjusting the spring pressure exerted upon the flint to cause the same to be under a substantially constant pressure.

Referring now specifically to the drawing, it will be seen that in Figs. 1 to 4 inclusive I show a general lighter body structure 1 of the usual type. Internally thereof is mounted a plate 2 which separates off the body portion 3 containing the volatile fluid from the operating mechanism. Passing through this top plate there is a pyrophoric element containing tube 4 and a wick tube 5. The pyrophoric element containing tube 4 extends from the bottom of the lighter 6, is bent at 7 and stops just short of the top plate 8. The wick tube 5, however, merely starts at or about the plate 2 and runs right through the top plate 8. The wick which passes through and is exposed at the upper end of such tube is freely immersed after it leaves the other end of such tube in the volatile fluid proper or in cotton wool, or the like, soaked in the volatile fluid contained in the body portion 3 of the lighter 1.

Located above this plate 2 is a hollowed out portion 9 into which fits the operating

mechanism which is more fully described hereinafter.

There appears in Fig. 1 at the top of the top plate 8 a portion of the operating mechanism, to wit, the thumb lever structure 10, the snuffer arm structure 11, the top of the wick tube 5 and the side plates 12, which side plates are secured to the top plate 8. The side plates 12 are each provided with three threaded holes 13, 14 and 15. Into these holes are threaded the pins 13', 14' and 15' which hold the side plates firmly apart, and about at least two of which pins (13' and 15') elements of the operating mechanism of the lighter are arranged to rotate.

The thumb lever structure 10, as will be seen in Fig. 3, consists in a thumb lug 16 secured to a bifurcated body portion 17 formed with arm portions 18 pivoted on the pin 15'. Disposed between the arms 18 of the body 17 and also pivoted on the pin 15' are the ratchet wheel 19 and the flint cutting wheel 20 which is secured to the ratchet wheel for rotation therewith. The snuffer arm 11 is pivoted for rotation on the pin 13' and is formed with the depression 21 at the end thereof, into, and against which depression, the end of the thumb lug 16 may seat to actuate the snuffer arm 11 on its pivot. The snuffer arm body 11 is also bifurcated and of hollowed out conformation having at the end thereof an extension portion 22. At the end of the bifurcated extension portion is a ratchet bar 23 pivoted on a pin 26. Secured in the extension portion is a retaining member 24 bent, as is shown in Fig. 6, to keep the ratchet bar 23 in proper alignment with the ratchet wheel 19. Passing transversely through the sides of the bifurcated extension 22 are pins 25 and 26. The retaining member 24 is secured against one of the sides of the extension 22 at the pin 25 by a washer 27. Due to its bent form the retaining or spring holding member 24, as will be observed in Fig. 6, operates to preserve the alignment of the ratchet bar 23 and, by holding the same firmly against the side of the extension 22, tends to frictionally maintain the angular displacement existing between the snuffer arm proper and the ratchet bar at different points along the stroke of such ratchet bar. Wound about the pin 13' is a spring 28 which is bent around and secured to pin 14' at one end thereof 28' and reversely bent upon itself and secured between washer 27 and the member 24 at the other end thereof 29.

The snuffer arm 11 has at the end thereof the usual snuffer cap 30 which is adapted to seat over and cover the end of the wick extending from the wick tube 5.

In Fig. 5 it will be noted that the ratchet bar 23 is shown as being somewhat bent at 31, so that the toothed portion thereof will register accurately with the longitudinal

midlength portion of the teeth of the ratchet wheel 19.

In the flint tube 4 a flint 32 is shown pressed against the flint cutting wheel under the influence of a plunger member 33 which is urged forward by a spring 34. Threaded into the end of the flint tube 4 is a plug member 35 having an extension 36, about which the spring 34 is disposed so that the same engages with the inner end of the plug member 35. This plug member shown in Figs. 8 and 9 is formed at its outer end with a slot 37. The bottom plate of the lighter is provided with the usual filling opening 38 into which is threaded a cap 39 for closing off the same. Centrally disposed on the threaded cap 39 is an extension 40, the end 41 of which is made of rectangular or square form so that the same may be used as a key to fit in the cavity or recess 37 in the plug 35 for turning the plug to adjust the pressure of the spring on the flint 32 and flint piston 33.

From the foregoing, the operation of my device will be observed to be substantially as follows:—When the thumb lever structure 10 is depressed by pressure brought to bear on the thumb lug 16, the body 17 is carried downwardly and rotates about the pivot pin 15'. As the end of the thumb lug 16 contacts with the depression 21 on the snuffer arm 11, the snuffer arm is rotated on its pin 13'. The snuffer arm is raised and the extension portion 22 is thereby lowered. The spring 28 due to the engagement of its bent over end 29 with the members 24 and 27 is tensioned; and the ratchet bar 23, carried by the extension 22, due to the shape of the plate 2 and also due to the member 24 causing such ratchet bar to frictionally engage with one side of the extension 22, rises and comes into engagement with the ratchet wheel 19. As the thumb lug is further depressed the snuffer arm and the snuffer cap 30 is further raised and the spring 28 further tensioned, due to the ratchet bar having become engaged with the ratchet wheel. Continued depression of the thumb lug 16 advances the ratchet bar forwardly from left to right of the lighter, as shown in Fig. 4, so that the ratchet and flint wheel secured thereto is rotated on the pin 15' to cut the flint and shower a series of hot sparks on the inflammable wick. At the end of the stroke the ratchet bar due to its form and due to the prechosen angularity of its teeth is disengaged from the ratchet wheel and may be freely withdrawn to its original position. The method employed for inserting and projecting the pyrophoric element in the structure shown readily lends itself to adjustability so that it is possible to maintain the pressure between the flint and flint cutting wheel constant throughout the life of a given flint.

It will thus be seen that I have created a novel cigar lighter structure, wherein there is contained means so arranged so that when pressure is brought to bear upon a portion of the lighter a novel coaction of elements results wherein a wick snuffer arm is removed from an inflammable wick and a shower of sparks is immediately thereafter thrown thereupon to ignite the same. It will be further noted that I have provided means for resiliently returning the various parts to their normal condition and also novel means of correlating and allocating the various parts.

Inasmuch as many changes may be made in the above construction and many apparently widely and different embodiments of the scope of the invention may be made without departing from the spirit and scope thereof, it is intended that all matter hereinabove contained or shown in the accompanying drawing shall be interpreted as illustrative and not in any way limiting. The following claims are intended to cover all of the generic and specific features of the invention described.

What I desire to secure by United States Letters Patent is:

1. In a cigar lighter having a body, a top plate, side plates atop said top plate, a snuffer arm pivoted between said side plates and having a bifurcated extension extending into said body, a ratchet wheel and a flint cutting wheel rotatably pivoted between said side plates, a member pivoted on the pivot for said flint cutting and ratchet wheels for actuating said snuffer arm on its pivot, a pivoted ratchet bar secured to and carried by said bifurcated snuffer arm extension, means in said bifurcated snuffer arm extension for maintaining said ratchet bar in alignment with said ratchet wheel, and resilient means on the snuffer arm pivot engaging with the means for maintaining the ratchet bar in alignment with the said ratchet wheel for normally returning all parts to original position.

2. In a cigar lighter structure substantially of the type described, a wick snuffer arm, a ratchet wheel, a pivoted ratchet arm of predetermined shape which, when in normal position, is at one end of its stroke and has its teeth thereof engaging with the teeth of said ratchet wheel, a thumb plate mounted atop said structure, means whereby thumb pressure when applied to said thumb plate in a line substantially vertical to the top plate of said lighter acts to cause said ratchet arm to go through a stroke and spin the ratchet wheel, means for withdrawing the ratchet arm from engagement with the ratchet wheel at the end of the stroke, means to normally return the thumb plate to its original position and the ratchet arm to its withdrawn position without engagement of its teeth with

those of the ratchet wheel, and means whereby primary raising of the pivoted snuffer arm brings said ratchet bar into re-inter-engagement with the teeth of the ratchet wheel.

3. In a cigar lighter, a casing, a partition extending across the entire cross section of the casing providing in conjunction with the upper end of the casing a pocket, a pyrophoric tube and a wick tube extending through said partition and terminating adjacent to the upper edge of the casing, a cap plate for said casing provided with vertically extending flanges on its sides, a rod secured in said flanges, a ratchet wheel and a flint cutting wheel mounted on said rod, a second rod secured in said flanges, a snuffer arm pivoted on said second mentioned rod, said snuffer arm being provided with an extension extending into said pocket, a driving ratchet secured to said extension and located in said pocket and operable to drive said ratchet and flint cutting wheels, an operating member pivoted on the rod supporting the ratchet wheel and flint cutting wheel and movable into said pocket, and spring means for returning said snuffer arm, ratchet bar, and operating member to normal position, said spring means being supported on said side plates and being connected to said extensions on said snuffer arm.

4. In a cigar lighter, a casing provided with an upwardly opening pocket extending across the entire cross section of the casing, a pyrophoric tube and a wick tube extending into said pocket, flanges on said casing, a flint cutting wheel supported on said flanges, a snuffer arm pivoted on said flanges, said snuffer arm being provided with an extension movable within said pocket, a driving device for said flint cutting wheel located in and operable within said pocket, an operating member movably mounted on said flanges and operable within said pocket, and spring means for returning said snuffer arm, driving device, and operating member to normal position, said spring being connected to said flanges and to said extensions on said snuffer arm.

In testimony whereof I have hereunto set my hand on this 28th day of October A. D., 1930.

JAMES FRANK ROGERS.
